UNITED STATES PATENT OFFICE.

ERSYLL F. CHAMBLESS, OF CHICAGO, ILLINOIS.

HAT COVER.

Application filed September 20, 1926. Serial No. 136,427.

This invention relates to protecting devices, and more particularly to a hat cover to be used for protecting hats during rain or inclement weather.

I am aware that various devices of this general character have been proposed, but, so far as I know, none of such devices have proved to be practical. In all devices of this general character with which I am familiar, it seems to be the accepted rule that it is necessary to provide draw strings, clips or clamps or equivalent members, tie strings, and various other impedimenta for securing the protector in position upon the hat. The result is that such devices usually present a grotesque and unsightly appearance and have not, for this reason, come into general use. A further objection to devices of this character, as heretofore constructed and used, is that such devices cannot be readily folded to form a neat compact bundle which can be readily carried in a lady's vanity case or purse or in a man's vest pocket or like limited space. This is frequently due to the provision of clamps, hooks, tie strings and various other impedimenta such as those above referred to which render it impossible from a practical standpoint to fold the device into a neat and compact package. A still further objection to devices of this general character which are secured to the hat, or, in some instances, to the wearer's head, is that a certain amount of inconvenience and annoyance is required in applying the device. For a device of this character to be practical, it is essential that it present a neat appearance when in use and that it can be quickly and easily applied and removed, and can be readily carried in a lady's vanity case, purse, or in a small pocket when not in use.

A primary object of my invention is to provide a hat protector or cover which avoids the above noted objections to devices of this sort as heretofore constructed and which can be readily produced at very small cost so as to enable it to be sold at such a price as to justify its general use. A further object is to provide a device of this character which, when applied, presents a neat appearance and which can be readily applied or removed with very little trouble. Another object is to provide a device of this character which, when not in use, can be readily folded in such manner as to provide a neat and compact bundle or package which remains flat and

can be readily carried in the pocket. Further objects will appear from the detailed description.

In the drawings:—

Fig. 1 is an elevation of my hat cover as applied;

Fig. 2 is a plan view of the hat cover in extended condition;

Fig. 3 is a fragmentary underneath view of the cover in extended condition; and

Fig. 4 is a plan view of the cover in folded condition to be carried in the pocket.

My hat cover is particularly adaptable for use in connection with the close fitting semi-toque type of hat such as is now commonly worn by women, and is of a bell shape, this type being known as the "cloche" hat. It will be understood, however, that my cover can be used in connection with hats of various types, and is equally applicable to men's hats.

My hat cover is formed from a sheet of suitable waterproof material, rubberized silk or pure rubber in suitable color being preferably used, though any other suitable material may be employed. As illustrated in Fig. 2, this sheet is of generally elliptical or oblong shape and is provided in each end with a V-shaped cut 1 extending from the lateral edges 2 of the sheet. The vertexes of the cuts 1 are on the medial line *a—a* of the sheet of material and separate it into two wing members 3. The lateral walls of the cut 1, together with the transverse line *a—b* extending from the vertexes of the cut transversely of the sheet define sectors *a—b—c* which are disposed in overlapping relation when the sheet is secured together at the ends of the wing members 3 to form an enclosing member or envelope to be positioned over the hat. The shape and size hat will determine the proportions and dimensions of the cover but the general pattern is substantially the same in all cases. As the lateral edges 2 of the wing members are arched or curved outwardly as illustrated, by overlapping the end portions or sector elements *a—b—c* of the wing members 3, these wing members can be secured together so as to form an envelope, in effect, of sufficient width to accommodate a hat *H* as in Fig. 1. As the ends or sector elements *a—b—c* of the wing members overlap, the resulting envelope is effectually closed at the front and back thereof so as to exclude moisture. By the provision of the sectors

100

105

110

at the ends of the wing members it is possible to vary the effective size of the cover by varying the extent to which these sectors overlap. For this purpose, I provide at each end of one of the wing members 3 two socket members 4 of snap fasteners of known construction. It is to be noted that these members 4 are disposed in alignment with each other and with the vertexes of the 10 V-shaped cuts 1. At each end of the other wing member 3 I provide two sets or series of studs 5 which cooperate with the socket members 4. As will be noted, the studs 5 of each set or series are disposed in alignment with each other and with the apexes of the V-shaped cuts 1. By arranging the studs and the sockets in this manner the sectors $a-b-c$ can be readily secured together in overlapping relation and the laps 15 of the sectors can be varied to vary the effective size of the cover so as to cause the same to fit snugly about and over the hat. In using the cover the ends of the wing members 3 are secured together in the manner above set forth, after which the resulting envelope is pulled down snugly over the hat, as in Fig. 1, effectually protecting the same. As the end portions of the wing members 3 are secured together in overlapping 20 relation and are adjusted so as to take up all looseness or flare, any bagginess or unsightly appearance in the cover when applied is eliminated, the resulting cover presenting a neat and pleasing appearance. 25 When the cover is not in use, it is removed from the hat and the end portions of the wing members are unfastened, the cover being then extended as illustrated in Fig. 2. After this has been done the cover is folded

first along the line $a-a$, then transversely 40 along the line $d-d$, after which it is folded along the line $e-e$. When folded in this manner the cover assumes the form illustrated in Fig. 4, and this forms a flat compact package or bundle which may be readily carried in the pocket with comfort. If desired, the cover may be rolled into cylindrical form making a very small package. As the socket members 4 and studs 5 are secured directly to the wing members, the 45 fastening devices employed do not in any way interfere with the folding and carrying of the cover. In view of the fact that this cover may be readily formed from a single sheet of waterproof material, and the studs 50 and socket members of the snap fasteners can be readily secured at small cost, the device, as a whole, can be produced at such a low cost as to justify its extensive use. In this connection, the ease with which the device 55 can be applied and removed, and its neat and attractive appearance in use, are important considerations.

What I claim is:—

In a hat protector, a flat sheet of material 60 of generally oblong shape provided with two V-shaped cuts disposed opposite to each other with their vertexes on the medial line of the sheet, said cuts separating the sheet 70 into two wing members, fastening means along the lateral edges of the V-shaped cuts and adapted to adjustably secure the ends of the winged members together when the said members are disposed in lapped relation.

In witness whereof, I hereunto subscribe my name this 15th day of September, 1926.

ERSYL F. CHAMBLESS.
